UNITED STATES PATENT OFFICE

RALPH C. COOLEY, OF HOUSTON, TEXAS

ARTIFICIAL TOOTH MOUNTING

Application filed August 12, 1929. Serial No. 385,257.

This invention relates generally to dentistry and more particularly to dental bridge-work.

The mounting of artificial teeth between natural teeth usually includes the connection of a bridge or backing, of gold or its harder alloys, to inlays, crowns or other attachments carried by the abutment teeth. On this backing are mounted the necessary number of artificial teeth, which are made of porcelain.

The defects of conventional bridgework are well known to the dental profession. Of these, perhaps the most objectionable is the lack of strength. The artificial teeth are usually so mounted that they are either weakened or improperly supported at the points of greatest strain, and are, therefore, unable to stand the strains to which they are normally subjected. Conventional bridgework is also objectionable because in order to replace one of a plurality of artificial teeth, the entire bridge structure must be removed. Furthermore, unnatural surfaces are presented which irritate the wearer's tongue, lips or cheeks, and prevent normal enunciation.

This invention has for one of its objects the provision of a new and improved backing and artificial tooth having interlocking means whereby the latter is rigidly and strongly supported.

Another object of the invention is to provide a new and improved backing and tooth embodying interlocking means so constructed that the tooth may be quickly and easily removed from the backing without disturbing the connection of the backing to the abutment teeth.

A further object is the provision of a structure of this type which will present surfaces so nearly resembling natural surfaces as not to irritate any part of the wearer's mouth, nor to impair his enunciation.

Various other objects of the invention will hereinafter appear.

In the accompanying drawings, which are illustrative of the preferred embodiment of the invention, Fig. 1 is a front elevation assembly view showing the bridgework con-

nected to abutment teeth, one of the artificial teeth being removed.

Figs. 2 to 5 are detail views of the tooth. Fig. 2 is a rear elevation; Fig. 3, a side elevation partly in section; Fig. 4, a front elevation; and Fig. 5, a perspective.

Figs. 6 to 9 are detail views of the backing corresponding to the detail views of the tooth.

Fig. 10 is a sectional side elevation of the assembled tooth and backing; and Fig. 11 is a section on the line 11-11 of Fig. 10.

Referring particularly to Fig. 1, the abutment teeth are indicated at 1, the roots thereof at 1a, the gum therebetween at 2, the backing at 4, and the artificial tooth at 3. This view illustrates the mounting of two artificial teeth between two natural teeth of the front portion of the upper jaw. One of these artificial teeth has been removed to illustrate its section of the backing. It will be understood that any number of natural teeth may be replaced by artificial teeth—incisors, cuspids, bicuspids or molars of either the upper or the lower jaw. The backing 4 will comprise a single section or several sections, depending upon the number of artificial teeth to be mounted. These sections, usually of gold, are ordinarily soldered together, and the end sections are then soldered to crowns, inlays or other metal attachment carried by the abutment teeth to hold the bridgework rigidly in place.

Referring now to the tooth per se, which is illustrated by Figs. 2 to 5, it is preferably made of porcelain, and has an upper gingival surface 3a which is to be fitted by the dentist to the shrunken gum, so that it occupies thereon an area equal to that formerly occupied by the original natural tooth. The artificial tooth closely resembles in appearance the natural tooth which it replaced, presenting normal surfaces inside, outside, and against the gum. And normal interspaces are left between the teeth so that they may be properly cleaned. This construction also presents natural feeling surfaces to the tongue and to the lips or the cheek, and permits normal enunciation.

The first inner wall 3b of the tooth shown

extends from the biting edge toward the gingival surface in a substantially vertical plane and has therein a substantially rectangular groove or pocket 3c. That end wall 3c' of this pocket adjacent the biting edge of the tooth is inclined toward said biting edge; and the other end wall 3c'' of this pocket is substantially parallel with the wall 3c'.

The second inner wall 3d of the tooth extends from its intersection with the first wall 3b toward the lingual and gingival surfaces of the tooth; the two walls being preferably at an obtuse angle to each other. On the wall 3d is a substantially triangular dovetail 3d' the apex of which is undercut as indicated at 3d''. From an inspection of Figures 2 and 5 it will be seen that this conforms substantially to the shape of the outline of the edges of the wall 3d, and that it is spaced inwardly from such edges around its entire margin. It will be observed that the wall of the dovetail 3d' is in the same plane with the end wall 3c'' of the pocket 3c.

The backing is illustrated by Figs. 6 to 9. It has a first wall 4b to engage the first wall 3b of the tooth and a tongue 4c on said wall shaped to snugly fit in the groove 3c of the tooth. The second wall 4d of the backing engages the second wall 3d of the tooth and is provided with a groove 4d' shaped for the snug reception of the dovetail 3d' of the tooth. The walls of the tooth and backing are preferably coextensive, as shown.

The engagement of the interlocking parts of the tooth and backing is shown quite clearly by Figs. 10 and 11.

The widths of the pocket 3c and the dovetail 3d' are but slightly less than the widths of adjacent parts of the tooth so that relatively great supporting walls are provided; but, as above explained, a marginal space 3e is left around the projection to allow room for trimming without disturbing the locking members, to shape the tooth and backing for insertion in the proper place between adjacent teeth. The pocket 3c is shallow, ordinarily of a depth much less than its width; and the tooth is, therefore, not weakened.

The backing and tooth are locked together by two tongue-and-groove joints. The extension of the backing into the tooth, and of the tooth into the backing insure rigidity and strength.

The undercut portion of the tongue 4c of the backing affords a strong support for the lower end wall 3c' of the tooth adjacent the biting edge; and the dovetail 3d' of the tooth is strongly supported by the walls of the groove 4d' of the backing; whereby the tooth is strongly supported at the points of greatest strain.

The tooth need be moved but a short distance upwardly and inwardly to mount it on the backing; and an equal distance downwardly and outwardly to remove it from the

backing. It therefore, may be easily removed from the backing without disturbing the connection of the latter to the abutment teeth.

The parts will be cemented together in the usual manner, but the cement will be subjected to no great strain; its sole necessary function being to preserve the engagement of the interlocking elements.

The invention is not limited to the specific embodiments and uses herein disclosed. Various changes may be made within the scope of the following claims.

I claim:

1. An individual porcelain saddle bridge-work construction comprising an interchangeable one-piece porcelain tooth having a gingival surface at one end and a biting edge at the other, said tooth being cut out at its lingual side to form two walls intersecting each other at an obtuse angle, the first wall extending from such intersection toward the biting edge, and the second wall extending from such intersection toward the lingual and gingival surfaces of the tooth, relatively wide interlocking means integral with and projecting from said second wall and extending to and integral with said first wall, interlocking groove means carried by the said first wall and of a transverse dimension substantially equal to the width of the first interlocking means, and a metallic backing having complementary walls and interlocking means shaped to snugly engage the corresponding elements of said tooth.

2. An individual porcelain saddle bridge-work construction comprising an interchangeable one-piece porcelain tooth having a gingival surface at one end and a biting edge at the other, said tooth being cut out at its lingual side to form two walls intersecting each other at an obtuse angle, the first wall extending from such intersection toward the biting edge, and the second wall extending from such intersection toward the lingual and gingival surfaces of the tooth, relatively wide interlocking means integral with and projecting from said second wall, said projecting means conforming in shape substantially to the outline of the edges of said wall and spaced inwardly from said edges around the entire margin thereof, and said projecting means extending to and being also integral with said first wall, interlocking groove means carried by the said first wall and of a transverse dimension substantially equal to the width of the first interlocking means, and a metallic backing having complementary walls and interlocking means shaped to snugly engage the corresponding elements of said tooth.

3. An individual porcelain saddle bridge-work construction comprising an interchangeable one-piece porcelain tooth having a gingival surface at one end and a biting

edge at the other, said tooth being cut out at its lingual side to form two walls intersecting each other at an obtuse angle, the first wall extending from such intersection toward the biting edge, and the second wall extending from such intersection toward the lingual and gingival surfaces of the tooth, relatively wide interlocking means projecting from said second wall and extending to said first wall, said means being integral with both walls, interlocking groove means formed in said first wall and extending from its point of juncture with said projecting means toward the biting edge of the tooth, said groove means being of a transverse dimension substantially equal to the width of the first interlocking means, and a metallic backing having complementary walls and interlocking means shaped to snugly engage the corresponding elements of said tooth.

In testimony whereof, I hereunto affix my signature.

RALPH C. COOLEY.
